CLAIM

The ornamental design for a direct-lit LED lighting fixture, as shown and described.

DESCRIPTION

FIG. 1 is a perspective view of a direct-lit LED lighting fixture;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The dashed or broken lines illustrate portions of the drawings that form no part of the claimed design.
